UNITED STATES PATENT OFFICE.

JAMES D. REIFSNYDER AND HENRY G. SCHWERDTLE, OF PHILADELPHIA, PENNSYLVANIA, ASSIGNORS TO STOKES & SMITH COMPANY, OF SUMMERDALE, PENNSYLVANIA, A CORPORATION OF PENNSYLVANIA.

MACHINE FOR FORMING SEALED WRAPPED PACKAGES.

1,152,357.

Specification of Letters Patent. Patented Aug. 31, 1915.

Application filed May 1, 1915. Serial No. 25,250.

To all whom it may concern:

Be it known that we, JAMES D. REIFSNYDER and HENRY G. SCHWERDTLE, citizens of the United States, residing at Philadelphia, in the county of Philadelphia and State of Pennsylvania, have invented new and useful Improvements in Machines for Forming Sealed Wrapped Packages, of which the following is a specification.

This invention relates generally to box or package wrapping or covering machines and more particularly to a machine for producing what will be termed a "sealed wrapped package," that is to say, a package wherein its covering wrapper is formed from a single adhesively coated blank having a body portion and integral side, end and top covering wings or flaps, all adherently affixed to all of the exterior walls of the box which forms a part of the package, the object being to provide a completely covered and sealed wrapped package.

Boxes wrapped and sealed in the manner described and as herein illustrated are especially adapted for use in connection with those classes of merchandise which are affected by atmospheric changes and conditions, or are subject to attack by certain species of vermin, and the packages made in a machine embodying the present invention are peculiarly adapted for use in connection with the manufacture and sale of various kinds of breakfast foods, baked products, such as crackers, biscuits, and the like, and various other classes of merchandise that are either subject to deterioration through changes in the atmosphere or attacks by vermin.

Another object of the invention is to provide a machine for adherently applying a single blank to all of the exterior walls of a box and wherein those portions of the blank that cover the various walls of the box are provided with printed matter constituting labels for the several walls of the box when the blank is applied thereto, the purpose being to so apply the blank to the walls of the box that when the box is opened for removal of its contents, the wrapper with its labels will not be destroyed as is the case with a wrapper that is loosely applied

to a box and which must be removed when the box is opened for removal of its contents.

The invention has for its purpose various other more or less important objects, all of which will appear from a reading of the following specification taken in connection with the accompanying drawings wherein we have illustrated and described one embodiment of the invention and one form of sealed wrapped package, it being understood that the present showing is only by way of illustration as we believe ourselves to be the first in the art to provide a machine for producing a completely covered and sealed wrapped package of the nature set forth.

In the drawing, Figure 1 is a vertical section showing a machine embodying the invention, certain parts being broken away. Fig. 2 is a vertical section through the same machine taken in a plane substantially at right angles to the plane of Fig. 1. Fig. 3 is a plan indicating the preferred form of wrapper blank upon which the machine operates to cover the box. Fig. 4 is a perspective illustrating a box or container such as may be covered with this wrapper blank by this machine. Fig. 5 is a diagrammatic view illustrating the mode of operation of the machine in applying the wrapper to the package. Fig. 6 is a diagrammatic plan indicating the next operation of the machine in applying the wrapper to the box. Fig. 7 is a side elevation further illustrating the operation indicated in Fig. 6. Fig. 8 is a side elevation diagrammatically indicating the next operation in applying the wrapper. Fig. 9 is a diagrammatic plan and partial section particularly illustrating the means for applying the projecting portions of the wrapper to the remaining uncovered side or wall of the box. Fig. 10 is a view similar to Fig. 9, but particularly illustrating the manner in which these instrumentalities co-operate. Fig. 11 is a vertical section further illustrating the operation of folding parts of the wrapper upon the uncovered side. Fig. 12 is a view indicating the next and last operation which effects the application of the long flap of the wrapper to the uncovered side or wall of the package. Fig.

- 13 is a fragmentary view showing diagrammatically and partially in section the mechanism for moving the package laterally to effect the application of the long flap of the 5 wrapper to the package. Fig. 14 is a perspective illustrating a completely covered package and particularly illustrating the manner in which the completely applied wrapper covers the box.
- 10 Before proceeding to a detailed description of the machine and its operation, it should be understood that fundamentally the function of the machine is to adhesively apply the wrapper to all the walls of a box, 15 except one, in such a way that there is a remaining area of the wrapper which is then applied to the remaining uncovered wall or portion of the side of the box. The sealed wrapped package produced by this machine, 20 is substantially air-tight, and this assists materially in preserving in a fresh state the contents of the package. Such packages are particularly desirable for candy, cereals, etc., crackers and biscuits.
- 25 The wrapper which is applied by the machine can be readily printed upon before its application and this obviates the necessity of applying any labels to the package after being delivered by the machine. This 30 greatly reduces the cost of the package. Furthermore, as the wrapper is adherent to the wall of the package at all points, it will not come loose from the package when the package is open, which insures that the 35 printing matter on the package remains intact.
- In Patent No. 1,131,792, issued March 16, 1915, one of the present co-applicants was a co-patentee. In that patent there was disclosed 40 a machine which operated to cover all sides of a box except one with the wrapper and this remaining uncovered side was afterward covered by a label. The application of this label entailed another operation and 45 materially increased the cost of producing the complete, sealed, wrapped package. The present invention operates upon an unwrapped box and applies a single wrapper blank to all of the walls of the box completely covering the box and delivers the 50 box ready for shipment and sale. Producing the completely wrapped box through the operation of one machine avoids rehandling the partly wrapped package and very 55 greatly increases the economy of operation and the amount of output or capacity of the machine. It also produces a neater package.
- Referring more particularly to the parts, 20 represents the frame of the machine 60 which may comprise a base 21, a lower table 22 and an upper table 23. The upper table 23 preferably is arranged to carry folding instrumentalities 24 for effecting the application of the wrapper to the package. In 65 order to clearly understand this operation,

reference should be had to Fig. 3 which illustrates the preferred form of wrapper blank which is to be applied to a package 25 such as illustrated in Fig. 4.

The wrapper blank 26 preferably comprises a body portion 27 of substantially rectangular form having integral side wings 28 and 29 and integral end wings 30. The side wings 28 and 29 have at their ends, end portions or corner laps 31 for a purpose 70 which will appear hereinafter. The wings 28 and 30 have marginal extensions 32 preferably as shown. Beyond the side wing 29, the wrapper blank has an integral long flap 33 which has substantially the same dimensions as the body portion 27.

The wrapper blank is smeared all over on one side with an adhesive or paste. In applying the wrapper to the package, the body portion 27 is applied to the bottom wall of 85 the package and the side wings 28, 29 and the two end wings 30 are folded up and secured to the side and end walls of the box, whereupon the margins 32 are folded in and secured to the remaining uncovered wall of 90 the box, and then the long flap or top flap 33 is folded over and secured to the remaining uncovered wall of the box.

In applying the wrapper to the box, the box is placed in an aligned position with the 95 body portion 27 of the blank so that the outline or edges 34 coincide with the edges of the bottom of the box. The wrapper and box are then placed upon the platen 35 of the machine which platen is preferably in 100 the form of a block having the same superficial dimensions on its upper face as the box to be covered, and furthermore, the platen preferably tapers in a downward direction (see Fig. 5). This platen 35 is carried on a spindle 36 which is guided to move vertically in the machine, the lower end of the spindle 36 being preferably provided with threads 37 to receive an adjustable collar 38, and the platen is raised and lowered 105 at the proper times through the medium of links 39 connecting with a lever 40 operated by a cam 41.

When the box and wrapper are placed on the platen 35 and the machine is started, 115 the cam 41 which is carried on the shaft 42 rotates, and the rotation of the shaft 42 operates to depress the plunger 43 through the medium of a cam 44 and a lever 45 which is connected with the plunger 43 at 120 46. The lever carrying the plunger may be provided with a suitable counterweight 47, and the plunger may be suitably guided in a guide-head 48 forming part of the post 49, extending upward from the upper table 125 23. The bottom face of the plunger 43 also has the same dimensions as the package so that when the plunger has come down, the box 25 will be held between the plunger and the platen in the manner indicated in 130

Fig. 5. The platen and plunger are then each positively actuated independently by their corresponding cams so as to hold and carry the box down between the wrapper applying instrumentalities which apply the different portions of the wrapper to the side walls of the box. This feature of positively actuating the platen independently of the plunger may evidently be embodied in machines for covering box shells.

The first operation in this machine consists in carrying the package down between two yielding wipers or brushes 48, the bristles of which engage the side wings 28 and 29 and fold them up against the vertical sides of the box, that is, against the walls that are at right angles to the bottom wall. After the wings 28 and 29 are secured, the end laps or corner laps 31 are folded around the corners of the box and secured to the ends. This is preferably accomplished in the manner indicated in Fig. 6 by means of yielding wipers or brushes 60 which move inwardly adjacent to the ends of the package. The arrangement and mode of operation of these brushes may be as desired. They may be mounted in the manner shown in Fig. 2, the brushes being supported upon bracket arms 61 adjustably mounted on parallel bars 62 disposed respectively on opposite sides of the throat or opening 63 in the machine through which the box passes. The bars 62 are preferably mounted on the ends of horizontally guided stems 64. At the proper times these stems are shoved inwardly. This may be accomplished if desired, by means of two rock levers 65, the upper arms of which are connected by a link 66 with the rear ends of the stems, the lower arms of the said levers being connected by links 67 with the main rock lever 68 pivotally mounted on a pin 69. This main rock lever 68 is a double bell crank lever having an arm 70 actuated by a slot 71 in a cam 72 carried on said cam shaft 42. After the side wings have been wiped against the sides of the box by means of the brushes 48, and before the end laps have been turned about the corners of the box in the manner stated, the box passes on between yielding rollers 49 which roll these vertical walls and insure a good contact between the wings 28, 29 and the side walls of the box. This downward movement continues and similar devices operate to fold the end wings 30 of the wrapper against the end walls of the box. These latter mentioned devices preferably comprise two brushes 51, the bristles of which engage the end wings 30 so as to wipe them up against the ends of the box, after which the package continues its downward movement between yielding rollers 52, which roll the attached wings 30 against the end walls of the box. The rollers 49 and the brushes 48 are suitably

supported in arms 53. The rollers 49 and 52 are preferably of a soft material such as rubber. If desired, the rollers may be resiliently yielding by means of any suitable construction such as that indicated at 54 70 in Fig. 1, in which the gudgeons 55 at the ends of the rollers are supported in brackets 56, which brackets have stems 57 passing through supporting brackets 58, the backward movement of the stems being resisted 75 yieldingly by means of coil springs 59 disposed around the stems. After the two side wings 28, 29 and the end wings 30 have been folded up and secured to the vertical walls of the package, it is then necessary to 80 fold over the margin flaps 32 to secure them to the remaining uncovered wall of the box. In order to accomplish this, the cam 44 is preferably constructed so that at the desired moment the plunger 43 will withdraw 85 slightly in the manner indicated in Fig. 11. Withdrawing the plunger in this way, of course, leaves the box on the platen unsupported.

Any suitable means may be provided for holding the box on the platen when the plunger has withdrawn in the manner suggested. However, for this purpose there is preferably provided a pair of oppositely disposed cleats which engage the opposite 95 ends and corners of the box. These cleats are automatically actuated to move inwardly at the proper time by a mechanism presently to be described and associated with the members or brushes which cause the margins 32 100 to fold over and secure themselves to the uncovered wall of the box. To fold over the margins 32, there is provided a pair of oppositely disposed folding members or brushes 74. These brushes are preferably 105 supported on suitable guide stems such as the guide stems 75 in Fig. 9, which are employed with a third brush or folding member 76. This brush 76 is similar in its functions to the brushes 74, but is made extensible and collapsible so that all three of the brushes may be advanced simultaneously. As the brushes 74 move inwardly toward each other, the brush 76 moves inwardly between them, but on account of its being collapsible, it does not obstruct their free inward movement. Any suitable construction such as this may be adopted for the brush 76 to enable it to allow for the presence of the other brushes or folding members. This 110 arrangement enables these instrumentalities or brushes to operate simultaneously upon the same wall of the box without interfering with each other.

In the present instance the brush 76 is 125 shown as consisting of a body member with extensible heads 77 at each end, said heads being pressed outwardly by a spring 78 and guided by means of guide stems 79, sliding in suitable sockets in the ends of the brush. 130

These three brushes are all moved inwardly by means of links 80 which are attached preferably at the middle points of the backs of the brushes. When the end 5 brushes 74 move inwardly the mechanism which operates them automatically moves in the clamping cleats 73. For this purpose, the cleats are carried on suitable guide stems 81 (see Fig. 1) 10 guided in the frame, and the links 80 are attached to small rockers 82. These rockers have cams 83 which engage the backs of the cleats and force them inwardly. At the same time, as the rockers 82 swing inwardly, 15 they operate to shove in on the links 80 so as to cause the brushes 74 to move transversely to the uncovered side of the box. A similar mechanism is provided for giving the intermediate brush 76 the same kind of 20 a movement, the rockers 82 corresponding to the three brushes, being actuated simultaneously by means of a rising and falling crosshead or sleeve 84 having three arms 85 which carry upwardly projecting stems 86 25 which are connected by links 87 with the aforesaid rockers 82. However, the intermediate brush 76 moves faster and further than the other two brushes. This is accomplished by making the arm 82^a of the rocker 30 corresponding to the brush longer than the corresponding arms of the other rockers (see Fig. 2). The box is now adherently covered on all sides except one remaining uncovered wall which in this instance is the upper wall 35 of the box. The machine now operates to fold down the unattached area of the wrapper and secure it to this uncovered wall. This is accomplished by any desired means which will operate to press the remainder 40 or unattached area or portions of the wrapper against the remaining uncovered wall throughout the entire area of this wall. In the present instance, this operation consists in folding down and attaching the long flap 45 33, and in the present instance this is accomplished by giving the partly covered box a lateral movement away from the plunger and platen. During this lateral movement the long flap is folded over and secured adherently to the box. In order to accomplish 50 this, there is provided an ejecting device 89 (see Figs. 2 and 13), which device preferably comprises a pusher 90 having a head 91 carried on two parallel guide bars 92 which 55 are supported and guided in suitable guide brackets such as the guide bracket 93, so as to enable the pusher to move in a horizontal path and transversely to the axis of the plunger 43 and the platen 35. In order to 60 actuate this pusher at the proper time, preferably the bars 92 are provided with a rigid and adjustable crosshead 94 which is attached to a link 95 connected to a lever 96. This lever is mounted on a pivot 97 and is 65 operated from time to time by a cam 98 on

the cam wheel 72. The lever 96 has a roller 99 which lies near the cam wheel 72. When the cam 98 comes around it strikes the roller and operates the lever to push the crosshead and pusher inwardly, this movement being 70 resisted by a coil spring 100 arranged around a stem 101 which is pivotally attached at 102 to the lever, and which slides freely through a guide 103. At the proper time this pusher 90 advances in the manner indicated in Fig. 13 so as to shove the package 25 off the platen 35. In order to fold down the long flap 33, it is preferable to provide near the path of lateral movement of the package, a fixed wiper or brush 104, the 80 bristles of which are arranged so that they will slightly press the upper wall of the package when the box passes under the brush. This mode of operation is clearly illustrated in Figs. 11 and 12. 85

It is understood that brushing a flap of the wrapper by yielding bristles in this way in applying it to the box is desirable because it removes the air bubbles or "blisters" which may tend to form between the wrapper and the wall of the package. In order to prevent the formation of any such "blisters" on the bottom wall of the package, it is also desirable to brush the bottom of the package while the same is having 90 this lateral movement. For this purpose, an auxiliary brush 105 is provided which is preferably adjustable in a vertical direction. For this purpose the brush is preferably formed on a bracket 106, the ends of 95 which are formed into adjustable clamps 107 received on downward extending guide bars 108 formed in the frame. The bristles 109 of this brush 105 project upwardly through an opening 110 in a plate 111. This plate 100 105 111 forms an extension of the bottom plate 112 of a chute 113 which receives the package after it passes the brushes 104 and 105 (see Figs. 12 and 2). This chute curves laterally and downwardly, preferably as indicated in Figs. 2 and 13, so as to deliver 110 the package at a convenient point.

In Fig. 14 is illustrated the completely formed sealed wrapped package 114, and in this package the long flap 33 forms the upper face. The long flap is usually printed upon so that in the completely covered box it forms a label. Means is provided for insuring that the pressure of the plunger and platen on the package will not be great 115 enough to injure the box. This pressure is preferably a yielding or spring pressure. In order to accomplish this, the spindle 36 is preferably not rigidly attached to the platen, but the platen has a shank 115 (see 120 Fig. 2) having a pin and slot connection 116 in the upper end of the spindle which is tubular at its upper end, and in the bore of the spindle at this point a helical spring 117 is provided which thrusts against the end 130

of the shank 115. The machine is adjusted so that the spring 117 will be slightly compressed when the plunger and platen are holding the package. By reason of this 5 spring evidently the plunger and platen will adapt themselves to hold and carry packages of slightly different depth. This overcomes any necessity for a very accurate construction of the cams which control the 10 plunger and platen. In other words, the spring allows for the slight variations in the depth of the boxes. The cam shaft 42 may be driven by a belt pulley 118 and clutch 119 through the medium of a worm 120 and 15 worm-wheel 121. In order to assist the machine operator in feeding the boxes and wrappers to the machine adjustable corner gages 122 are provided (see Fig. 2) which insure alinement of the box and wrapper 20 with the platen.

The blank as shown in Fig. 3 is preferably formed so that the marginal portions 32 are of the same length as the wings or flaps of which they form a part, and the 25 ends of these marginal extensions are preferably clipped on an inclined line. On this account, when these portions are folded in on to the remaining uncovered wall of the box, they simply lie flat upon the wall without 30 producing any doubled edge or gusset fold. At this point and at all other points of the wrapper there are no overlapping portions of the wrapper that are not either adherently attached to the wall of the box 35 or to the other portions of the wrapper. Thus, we absolutely eliminate the presence of crevices in which insects might find lodgment. When the box is completely covered with the wrapper, the portions of the wrap- 40 per which correspond to the different walls have their edges coinciding with the edges of the package so that the printed matter indicated at 33^b on the wrapper presents itself properly alined and the same effect 45 is produced as though different labels had been applied to the different sides of the box which carry the printed matter.

We do not limit ourselves to the use of all the features of our invention in combination, as we may use any of the features separately.

It is understood that the embodiment of the invention described above is only one of the many forms or embodiments the invention may take, and we do not wish to be limited in the practice of the invention nor in our claims to the particular embodiment set forth.

What we claim is:

60 1. A machine for completely covering the exterior walls of a box with a single adhesively coated blank having a body portion and integral side, end and top covering flaps all adherently attached to the several walls 65 of the box, comprising means for supporting the box and its covering blank, flap applying instrumentalities for successively applying some of the adhesively coated flaps to the side and end walls of the box, means for moving the said supporting means with the 70 box and its blank through the said flap applying instrumentalities to have the flaps adhesively applied to the said side and end walls of the box, and means operating after the application of the said side and end covering flaps for adherently affixing the remaining adhesively coated portions of the blank to the top wall of the box throughout the entire area of said top wall and said 75 remaining portions of the blank whereby to 80 provide a completely covered and sealed box.

2. A machine for completely covering the exterior walls of a box with an adhesively coated blank having a body portion and integral side, end and top covering flaps adhesively attached to all of the exterior walls of the box, comprising movable means for supporting the box and its covering blank with the bottom of the box resting upon 90 and adhesively attached to the body portion of the blank, flap applying instrumentalities for successively applying some of the adhesively coated flaps to the side and end walls of the box, including means for folding end portions of some of the flaps around the vertical corners of the box, means for moving the said box and its blank through the said flap applying instrumentalities to have the adhesively coated flaps applied to 95 all of the side and end walls of the box, and means operating after the application of the flaps to the said side and end walls to adhesively apply the said adhesively coated top covering flap of the blank to the top 100 wall of the box throughout the entire area of said top covering flap whereby to provide a completely wrapped and sealed box.

3. A machine for completely covering the exterior walls of a box with an adhesively coated one-piece wrapper having integral flaps corresponding to the walls of the box to produce a sealed wrapped package, comprising in combination, means for supporting said wrapper and the box with a wall of the box resting upon an adhesively coated portion of the wrapper, means for folding up and adhesively affixing some of the adhesively coated flaps of the wrapper to the walls of the box lying at right angles to the first named wall to adhesively attach the same thereto and thereby effect the adhesive application of such portions of the wrapper to all of the aforesaid walls of the box, and means for adhesively applying the unattached remainder of the wrapper to the wall of the box opposite the said first named wall, said means operating to press the said remainder of the wrapper against said last named wall throughout the entire area of 115 120 125 130

the said remainder of the wrapper to effect the adhesive attachment thereof whereby to provide a completely covered and sealed wrapped package.

wall, one of said members being collapsible to allow for the presence of the other member.

10. In a machine for applying an adhesively coated wrapper to a box, in combination, means for applying the wrapper to all walls of the box save one so that the wrapper presents flaps projecting beyond the uncovered wall, a brush movable transversely of the uncovered wall to apply one of said flaps to said uncovered wall and another brush movable transversely of said uncovered wall in a path transverse to the direction of movement of said first-named brush 15 to apply another of said flaps to the uncovered wall, one of said brushes being extensible and collapsible to prevent the same from arresting the movement of the other brush.

20. 11. In a machine for applying an adhesively coated wrapper to a box, in combination, means for applying the wrapper to all walls of the box save one so that the wrapper presents flaps projecting beyond the uncovered wall, a pair of brushes movable toward each other from opposite sides and transversely of the uncovered wall to apply an opposite pair of said flaps to said uncovered wall, and another brush movable transversely 25 of said uncovered wall between said brushes and in a path transverse to their direction of movement to apply another of said flaps to the uncovered wall, said last-named brush being extensible and collapsible longitudinally to prevent the same from arresting the movement of the other brushes.

12. In a machine for applying an adhesively coated wrapper to a box, in combination, means for applying the wrapper to all 40 walls of the box save one so that the wrapper presents flaps projecting beyond the uncovered wall, a pair of brushes movable toward each other from opposite sides and transversely of the uncovered wall to apply an opposite pair of said flaps to said uncovered wall, another brush movable transversely of said uncovered wall between said first-named brushes and in a path transverse to their direction of movement to apply another of said flaps to the uncovered wall, a fixed brush opposite said last-named brush, and means for moving the box laterally and under said fixed brush to apply the fourth flap of the wrapper 45 per to the uncovered wall.

13. In a machine for applying an adhesively coated wrapper blank having a long flap, to all the outer walls of a package, in combination, a platen for supporting the wrapper with the package resting on the wrapper, a plunger for engaging the upper horizontal wall of the package, wrapper-applying instrumentalities for applying portions of the wrapper blank to the vertical walls of the package, means for with-

drawing said plunger from the upper horizontal wall of said package to leave the upper horizontal wall unobstructed, movable brushes moving inwardly from three sides for engaging portions of the wrapper to 70 fold the same downwardly and secure the same to the upper horizontal wall of the package, means for moving the package thereafter in a lateral path, and a fixed brush adjacent the lateral path of movement of the package for engaging the long flap and for folding the same down upon the upper horizontal face of the package.

14. In a machine for applying an adhesively coated wrapper blank having a long flap, to all the outer walls of a package, in combination, a platen for supporting the wrapper with the package resting on the wrapper, a plunger for engaging the upper horizontal wall of the package, wrapper-applying instrumentalities for applying portions of the wrapper blank to the vertical walls of the package, means for withdrawing said plunger from the upper horizontal wall of said package to leave the upper horizontal wall unobstructed, movable brushes moving inwardly from three sides for engaging portions of the wrapper to 80 fold the same downwardly and secure the same to the upper horizontal wall of the package, means for moving the package thereafter in a lateral path, a fixed brush adjacent the lateral path of movement of the package for engaging the long flap and for folding the same down upon the upper horizontal face of the package, and another brush near the lateral path of movement of the package for engaging the lower horizontal face of the package to press out the air bubbles, between the wrapper and the 85 package, on the bottom of the package.

15. In a machine for applying an adhesively coated wrapper blank having a long flap, to all the outer walls of a package, in combination, a platen for supporting the wrapper with the package resting on the wrapper, a plunger for engaging the upper horizontal wall of the package, wrapper-applying instrumentalities for applying portions of the wrapper blank to the vertical walls of the package, means for withdrawing said plunger from the upper horizontal wall of said package to leave the upper horizontal wall unobstructed, means moving inwardly from three sides of the 90 package for engaging portions of the wrapper to fold the same downwardly to secure the same to the upper horizontal wall of the package, an ejecting pusher and means for advancing the same to move the package laterally from the platen, fixed means adjacent the lateral path of movement of the package for engaging the long flap and for folding the same down upon the upper horizontal face of the package, and a spring 95 100 105 110 115 120 125 120 125

for effecting the return of the said pusher after ejecting the package.

16. In a machine for applying an adhesively coated wrapper blank having a long flap, to all the outer walls of a package, and in combination, wrapper applying instrumentalities operating successively to apply portions of the wrapper blank to the vertical walls of the package, a platen and a plunger for engaging the opposite horizontal walls of the package, means for positively actuating said plunger and means for simultaneously positively actuating said platen to hold and carry the package and its wrapper blank through the said wrapper applying instrumentalities, means for ejecting the partially covered package from between the said plunger and platen, and means adjacent to the path of movement of the ejected package for applying the said long flap of the blank to a wall of the package as the latter is being ejected.

17. In a machine for applying an adhesively coated wrapper blank to all the outer walls of the package, and in combination, wrapper applying instrumentalities operating successively to apply portions of the wrapper blank to the vertical walls of the package, a platen and a plunger for engaging opposite horizontal walls of the package, means for actuating said plunger and platen to carry the package and its wrapper blank through the said wrapper applying instrumentalities, means for effecting a withdrawal of said plunger from the upper horizontal wall of the package, means for engaging the vertical walls of the package for holding the same in place on the platen when said plunger is withdrawn, said wrapper applying instrumentalities including means for folding in the marginal portions of the wrapper on the upper side of the package adjacent to said plunger, means for moving the partially covered package in a lateral path, and means adjacent the lateral path of movement of the package for applying the said long flap of the blank to the upper horizontal wall thereof.

18. In a machine for applying an adhesively coated wrapper blank having a long flap, to all the outer walls of a package, and in combination, wrapper applying instrumentalities operating successively to apply portions of the wrapper blank to the vertical walls of the package, a platen and a plunger for engaging the opposite horizontal walls of the package, means for positively actuating said plunger and means for simultaneously positively actuating said platen to carry the package and its wrapper blank through the said wrapper applying instrumentalities, yielding means associated therewith to cause the platen and plunger to hold the package yieldingly therebetween, means

for ejecting the partially covered package from between the said plunger and platen, and means adjacent to the path of movement of the ejected package for applying the said long flap of the blank to a wall of the package as the latter is being ejected.

19. A machine for completely covering the exterior of a box with an adhesively applied one-piece wrapper having integral flaps corresponding to the walls of the box to produce a sealed wrapped package, comprising in combination, means for supporting the wrapper and the box with a wall of the box resting on the wrapper, means for folding up and adherently affixing all except one of the integral flaps against the adjacent walls of the box to adhesively attach the same thereto and thereby effecting the adhesive application of the wrapper to all of the walls of the box except the remaining wall opposite to said first named wall, and means for adhesively applying the remaining unattached portion of said wrapper to said remaining wall, said means operating to press said remaining unattached portion against said remaining wall throughout the entire area of said remaining wall to effect the adhesive attachment of said last named flap.

20. A machine for completely covering the exterior walls of a box with an adhesively coated one-piece wrapper having integral flaps corresponding to the walls of the box to produce a sealed wrapped package, comprising in combination, means for supporting the said wrapper and the box with a wall of the box resting upon an adhesively coated portion of the wrapper, means for folding up and adherently affixing some of the adhesively coated flaps of the wrapper to the walls of the box lying at right angles to the first named wall to adhesively attach the same thereto and thereby effect the adhesive application of such portions of the wrapper to all of the aforesaid walls of the box, means for moving the box laterally thereafter and means operating upon the box in its lateral movement for adhesively applying the unattached remainder of the wrapper to the wall of the box opposite the said first named wall.

21. A machine for completely covering the exterior walls of a box with a single adhesively coated portion of the wrapper blank having a body portion and integral side, end and top covering flaps all adherently attached to the several walls of the box, comprising means for supporting the box and its covering blank, flap applying instrumentalities for successively applying some of the adhesively coated flaps to the side and end walls of the box, means for moving the said supporting means with the box and its blank through said flap applying instrumentalities to have the flaps adhesively applied to the said side and end

walls of the box, means operating thereafter to move the box in a lateral path, and means for folding said top covering flap and for adherently affixing the same to the top wall 5 of the box while the box is moving in said lateral path.

In testimony whereof we have hereunto

set our hands in presence of two subscribing witnesses.

JAMES D. REIFSNYDER.

HENRY G. SCHWERDTLE.
